UNITED STATES PATENT OFFICE.

BENJAMIN T. HEADLEY, PARKE H. THOMPSON, AND DAVID IRVIN DU BOIS, OF MILLVILLE, NEW JERSEY, ASSIGNORS TO WHITALL-TATUM COMPANY, OF MILLVILLE, NEW JERSEY, A CORPORATION OF NEW JERSEY.

VIAL-BOTTOMING MACHINE.

Application filed November 15, 1919. Serial No. 338,179.

To all whom it may concern:

Be it known that we, BENJAMIN T. HEADLEY, PARKE H. THOMPSON, and DAVID IRVIN DU BOIS, all citizens of the United States, 5 and residing at Millville, in the county of Cumberland and State of New Jersey, have invented a new and useful Improvement in Vial-Bottoming Machines, of which the following is a full, clear, and exact description.

This invention relates to an improvement in vial bottoming machines, and is designed to provide an efficient and simple automatic machine for rapidly bottoming vials.

One of the objects of our invention is to provide a machine having an endless carrier which is moved step by step to successively bring the different blank supports with their blanks thereon to a plurality of heating stations at which the blanks are heated. The blanks are first brought to a heating station at which the blanks are partially heated, and are then successively moved to different heating stations whereby they are 20 additionally and gradually heated to the proper temperature, after which they are moved to the blank separating and bottoming station or stations. By the provision of a plurality of heating stations, we are enabled to construct a machine in which the output is limited only by the time required for bottoming, as the mechanism is so arranged that immediately after one blank has been bottomed it is moved away from 25 the bottoming mechanism and the next blank which has been heated to the proper temperature is immediately shifted to the bottoming station and is acted upon by the mechanism.

A further object of our invention is to provide a compound driving mechanism for a vial necking machine and a vial bottoming machine which is arranged to actuate the two machines in timed relation to each 40 other, together with suitable feeding and transfer mechanism for feeding the necked blanks to the bottoming machine.

Another object of our invention is to provide suitable clutch devices in connection 45 with the driving mechanism, so arranged that either of the two machines can readily be connected or disconnected from the driving mechanism.

Still another object of the present invention is to provide a bottoming machine 55 which may be fed from any suitable type of feed device.

The precise nature of our invention will be best understood by reference to the accompanying drawings, which will now be 60 described, it being premised, however, that various changes may be made in the details of construction, and the general arrangement of the parts, without departing from the spirit and scope of our invention, as 65 defined in the appended claims. In the drawings—

Figure 1 is a plan view of one form of machine built in accordance with our invention;

Figure 2 is a side elevation of the machine shown in Figure 1;

Figure 3 is a plan view of the driving mechanism;

Figure 4 is a sectional view on the line 75 IV—IV of Figure 1, showing a portion of the machine;

Figure 5 is a detailed sectional view illustrating the worm driving mechanism on one end of the machine;

Figure 6 is a section view on the line 80 VI—VI of Figure 5;

Figure 7 is a side elevation of the transferring mechanism for transferring the blanks to the bottoming machine, and in 85 which the blank supporting member has been moved into engagement with the blank;

Figure 8 is a similar view, in which the blank has been moved to a point above one 90 of the supports on the endless carrier;

Figure 9 is a view similar to Figure 8, in which the supporting member has been moved away from the blank and the blank deposited on the blank support on the endless carrier;

Figure 10 is a side elevation of the transfer mechanism;

Figures 11 and 12 are sectional views on the lines XI—XI and XII—XII, respectively, of Figure 10;

Figure 13 is a longitudinal sectional view of one end of the bottoming machine showing feeding mechanism for feeding blanks from a vial necking machine or other suitable source to a point where they are en-

gaged by the transferring mechanism and transferred from the feeding mechanism to the bottoming machine;

Figure 14 is a plan view of a form of driving mechanism for connecting the bottoming machine to a necking machine;

Figures 15 and 16 are views largely diagrammatic illustrating the steps of separating and bottoming the blank;

10 Figure 17 is a detail sectional view of the bottoming device;

Figure 18 is a diagrammatic plan view of a preferred form of our invention;

Figure 19 is a side elevation of Figure 15;

15 Figure 20 is an enlarged detail view of the extending, separating and bottom operations;

Figure 21 is a side view of one end of the bottoming machine having a modified 20 form of feeding device;

Figure 22 is a longitudinal sectional view of the mechanism disclosed in Figure 21;

Figure 23 is a perspective view of the modified or hopper form of feed device;

25 Figure 24 is a transverse sectional view on the line XXIII—XXIII of Figure 21;

Figure 25 is a side elevation of a necked blank of the type which may be fed to the bottoming machine, and

30 Figure 26 is a view corresponding to Figure 25 of a straight blank for wide-mouthed vials.

In the drawings, the reference character 2 designates the frame of the machine, and 35 rotatably supported in suitable bearings mounted on the frame 2 are shafts 3 and 4, which carry sprocket wheels 5 and 6 respectively. There is provided an endless carrier 7, built up of two parallel endless link 40 belts, each of which engages one of the sprocket wheels 5 on the shaft 3 and one of the sprocket wheels 6 on the shaft 4. Connected to each of the link belts 7 are a plurality of blank carriers 8, the blank 45 carriers on one belt being in transverse alignment with the blank carriers on the other belt. These belts are provided with suitable rollers 9 which engage tracks 10 carried by the frame 2 (see Figures 3 and 4) and extending from the sprocket wheels 6 to the sprocket wheels 5 for supporting the link belts 7 in a horizontal plane from the centering station to a point slightly beyond the finishing station. In actual practice we may provide idler sprockets, 50 adjustably attached to the side frame 2, for taking up the slack in the chains. These sprockets may be similar in construction and operation to the sprockets illustrated in Figure 13 for the chain 106, and are therefore not illustrated in detail.

Rotatably mounted in suitable bearings in each of the blank supports 8, are rotating rollers 11 and 12, the spindles of which 55 extend laterally from the supports and are

each provided at one end with extended rollers 11' and 12', and at the other end with a worm wheel 13 and 14 respectively. These worm wheels 13 and 14 for the rollers of the supports at one side of the machine 70 are in engagement with a worm 15, while the worm wheels for the supports on the other side of the machine are in engagement with a similar worm 15^a. These worms 15 and 15^a may be journaled in suitable center 75 bearings such as shown at 16 in Figure 5 and Figure 1, which bearings are adjustable in suitable brackets connected to the frame of the machine.

There is a main driving shaft 17 having 80 a pulley 18 thereon, which may be driven by means of a belt (not shown) from any suitable source of power. Connected to the shaft 17 is a pinion 19 which drives a gear wheel 20 on the shaft 21, and operatively 85 connecting the shaft 21 and the shaft 3 is a Geneva gear 22 for intermittently rotating the shaft 3. On each end of the shaft 21 is a spiral gear 23, the one at one end meshing with a spiral gear 24, while the one at the other end meshes with a spiral gear 24^a, carried respectively, by longitudinal cam shafts 25 and 25^a. These cam shafts 25 and 25^a are journaled in suitable bearings 26 on the frame of the machine, and are provided with thrust ball bearings 27 and 27^a to reduce friction. The shaft 21 need not be provided with thrust ball bearings as the spiral gears 23 on the ends thereof produce 90 equal and opposite forces. Connected to the shaft 25 is a second spiral gear 28, meshing with a spiral gear 29 on a transverse shaft 30, journaled in suitable bearings on the frame of the machine, and also provided with a thrust ball bearing 31.

The front end of each of the worms 15 and 15^a is provided with a bevel gear wheel 32. Each of these gear wheels is in mesh with a gear wheel 33 and connected to each gear wheel 33 is a pinion 34. The gear wheels 33 and the pinions 34 are rotatably mounted on stub shafts 35, each of which is mounted in the bracket having the bearing 16 in the front end of the worm shafts 15 and 15^a. Mounted on the shaft 30 at 100 each side of the machine, and adjustable about the axis thereof, is a forked bearing member 36, and connected to the shaft 30 between the forked arms of the bearing member 36 is a gear wheel 37. Each of the gear wheels 37 meshes with accelerating gears 38 rotatably mounted on a pin 39 in the bearing member 36, and one of said accelerating gears meshes with the pinion 34, so that the worms 15 and 15^a are driven by means of the shaft 30 through the above described connections. The bearing members 36 are each provided with a sector having a slot 40 therein for the reception of a clamp screw 41 adjustably securing the bearing 36 110

to the frame 2. By this arrangement the accelerating gears 38 can be properly engaged with the teeth of the pinions 34. The shaft 17 is continuously driven from the 5 source of power, and in turn continuously rotates the shaft 21, which in turn operates the shaft 3 step by step by means of the Geneva gear before described, to move the blank supports to the different successive stations at which the blanks are operated on as hereinafter described. As the worms 15 and 15^a are connected to the shafts 25 and 30 by means of the accelerating gearing heretofore described, the worms will be 10 continuously driven and by means of the worm wheels 13 and 14 will rotate the rollers 11 and 12 for the blank supports 8, so that the blanks will be continuously rotated while at the different stations. Each blank 15 is first fed to a station A (see Fig. 2), from which it is transferred by a suitable transfer mechanism, to be hereinafter described, to the station B. The carrier is then moved 20 to bring the blank to the station C, at which point the blank is moved to a central position with relation to the blank supports on the two link belts. After the blank has been moved to its central position, the carrier is again moved another step to bring 25 the support with the blank thereon to the station D', at which point the blank is initially heated by suitable burners herein-after more fully described, and which may be of any approved type and extending up 30 from below as well as from above, between the supports on the two chains. The blank is then moved to station D^a, at which point it is still further heated by suitable burners and is then moved step by step to the stations D^b, D^c and D^d, at which stations the further heating to proper operating temperatures takes place. By the time the blank is ready to leave station D^d it has 35 been heated to the proper point for bottoming, and is moved from there to the station E, at which point the ends of the blank are pulled laterally to separate the blank, and after such separation, a bottom-forming device is moved up between the two portions 40 and afterwards the portions are moved toward the bottoming device. After the portions have been bottomed they are moved to the station F from which they are removed from the supports and fed into a 45 suitable chute.

The mechanism for transferring the blanks from the station A to the station B may comprise a lever 42 pivoted at 43 to a bracket 44 on the frame 2 of the machine. 50 This lever 42 has an extension 45 which is connected to a lever 46 by means of a link 47. The lever 46 is carried by a pin 48 mounted in bearings on the frame of the machine. Connected to the shaft 30 adjacent the lever 46, is a cam 49 having a groove 50

therein for the reception of a roller 46' on the lever 46, this mechanism being arranged to shift the lever 42 from the position shown in Figure 7 to the position shown in Figure 8. Pivotedly mounted on the pin 43 and 70 at the side of the lever 42 is a second lever 51 located between the stop pins 52 on the lever 42. Slidably mounted in one end of this lever 51, is a stem 53, having connected to the upper end thereof a V block 54. The 75 stem 53 is held in position in the slotted end of the lever 51 by means of plates 55, which are connected to the lever 51, and connected to the stem 53 and extending through a slot in one of the plates 55 is a 80 roller 56. This roller 56 also extends into a cam slot 57 in the lever 42. The lower end of the lever 51 is provided with a segmental friction strip 58, which is engaged on each side thereof by leather-faced friction strips 59 supported on the bracket 44. The bracket 44 is forked as clearly shown in Figure 11, and each fork thereof is provided with a plurality of hollow bosses 60, and openings 70. Threaded into each of 90 the plates 59 are three tap screws 71, extending through the openings 70, while short pins 72 also connected to the plates extend into the bosses 60. Springs 61 are provided within the recesses in the bosses 60, and at 95 one end engage the plates 59, while at the other end they engage followers 62 adjustable by means of set screws 63 mounted in screw plugs 64 in the ends of the bosses 60. By adjusting the screws 63 the friction between the plates 59 and the friction member 58 on the lever 51 can readily be varied. When the parts are in the position shown in Figure 2, the V block 54 has been brought to a position under the blank at station A. 100 As the cam 49 is rotated, the lever 46 will be depressed and during the first part of the travel will move the lever 42 with relation to the lever 51, the lever 51 being held by the friction plates 59. This movement 105 of the two levers relative to each other will elevate the V block 54 and lift the blank at the station A from its support, see Figure 7. The further movement of the lever 46 will bring the transfer mechanism to the 110 position shown in Figure 8 in which the vial blank is above the blank support at the station B. The roller on the lever 46 is now at the high point of the groove 50 in the cam 49 and immediately thereafter the 115 lever 46 will be raised to reverse the movement of the parts. During the first raising movement of the lever 46, the lever 42 will be moved with relation to the lever 51, and during this relative movement of these 120 two levers the V block 54 will be lowered and will deposit the blank on the blank support at station B, and at the same time the roller 56 will travel to the reverse side of 125 the slot 57 as shown in Figure 9. A fur- 130

ther movement of the lever 46 will return the transfer mechanism to the position shown in Figure 2.

The centering mechanism at station C may 5 comprise shiftable rods 65, one on each side of the machine, arranged to reciprocate in bearings in brackets 66 on the frame of the machine, and adapted to be reciprocated by levers 67 which are in turn actuated by cams 68 on the shafts 25 and 25^a. As the centering mechanism is identical with similar 10 mechanism at the finishing station with the exception of the shape of the groove in the cams 68, a detailed description of this mechanism 15 will be given in connection with the bottoming mechanism, it being deemed sufficient at this time to state that when the rods 65 are reciprocated toward one another they engage the opposite ends of the vial blank 20 to properly position the same on its support.

At the finishing station E there are provided reciprocable rods 69 similar to the rods 65 at the centering station before referred to. As the rods on opposite sides of the machine 25 are duplicates of each other, we will, for sake of clearness, only describe the connections and operation of one of said rods. This rod 69 is adjustably mounted in a bushing 70, connected to which is a yoke 71 which 30 is arranged to be adjusted along the length thereof between the bearings 72 on the bracket 73. The yoke 71 is connected to one end of a lever 74 by means of a link 75. The other end of this lever 74 is pivotally connected to a bracket 76 carried by the frame 35 of the machine. Extending laterally from one side of the lever 74 is a roller 77 which is seated in a groove 78 in a cam 79. At one side of the machine, the cam 79 is splined to the shaft 25, while at the other side the corresponding cam is carried by the similar 40 shaft 25^a. The end of each of the rods 69 adjacent the center of the machine is bored out for the reception of a spindle 80 on a disk 81. Surrounding the spindle 80 and 45 interposed between the disk 81 and the end of the rod 69 is a ball bearing 82. A spring 83 is seated in the rod 69, bearing against the end of the spindle 80, holds the disk 81 in extended position, and forms a 50 resilient stop when the disk 81 engages the bottle or vial as hereinafter described, to prevent breaking and accommodate slightly varying blank lengths.

55 Mounted on each side of the machine at the finishing station E is a retracting device each of which is carried by a bracket 84 on the frame of the machine. Each of these retracting devices, and for sake of clearness 60 only one will be described, comprises a friction roller 85 which is journaled on a bell crank 86 having a pivotal connection 87 to the bracket 84. Secured to the friction roller 85 is a worm wheel 88 which is engaged by a worm 89 journaled in a bearing on the bell

crank 86. This worm 89 is flexibly connected to the shaft of a bevel gear 90 by means of a universal connection 91. The shaft of the bevel gear 90 is journaled in a bearing on the bracket 84, and rotatably mounted in a 70 second bearing in this bracket and at right angles thereto is a vertical shaft carrying a bevel gear 92, meshing with the bevel gear 90. The other end of this shaft is preferably provided with a worm wheel 93, which engages either the worm shaft 15 or 15^a according to the side of the machine, so that the friction roller 85 is continuously rotated, and is arranged when moved into contact with a vial blank to move the vial blank endwise toward and against the disk 81 on the end of the rod 69. Connected to one arm of the bell crank 86 and a similar arm of a bell crank 94 is a link 95, the length of which can readily be adjusted by a suitable turn buckle 85 or the like. The other arm of the bell crank 94 is provided with a roller 95' which engages the periphery of a cam 96, secured to one of the shafts 25 or 25^a. The roller on the bell crank 94 is held in contact with this 90 cam by means of a spring 94' which is seated in a recess in the bracket 84 and engages one of the arms of the bell crank 94.

Slidably mounted in suitable guides 97 on the tracks 10 at the finishing station E (see 95 Figure 4) is a bottoming device 98, the upper end of which is provided with disks 99 which may be arranged to freely rotate therein. The lower end of this bottoming device 98 is provided with a roller 100 in 100 engagement with the periphery of a cam 101 connected to the shaft 21, and is arranged to be held against the cam by means of a spring 102 (see Fig. 17) seated in a recess 105 in the guide 97 and engaging a laterally extending arm 98^a on the bottoming member 98.

In the operation of the machine, the shafts 3 and 4 are intermittently rotated, while all of the other shafts together with 110 the cams connected thereto, are continuously rotated. The blanks are first transferred to a support at station B, and the carrier is then moved a step to bring the vial to the centering station C. The plungers or rods 115 65 are then moved toward each other to center the blank with relation to the support and after the blank has been centered it is moved step by step to the different heating stations. When it has been moved to 120 the bottoming station the rods 69 are moved toward each other by the cams 79 and the friction rollers 85 are then moved into contact with the blanks by the short high-points 96^a on the cams 96 to separate the blank at 125 its heated portion and move the neck ends thereof against the disks 81. At about this time the bottoming member 98 is moved upwardly by its cam 101 and the friction rollers 85 are removed from the blanks, the rollers 130 85 are removed from the blanks, the roll-

ers 95' having left the short high-points 96^a on the cam 96. The blanks are then moved toward the bottoming device by the rods 69, during which time they are continuously rotated so that when the blanks engage the bottoming device perfect bottoms will be formed thereon. Shortly after the blanks have been moved against the bottoming device, the long high-points 96^b on the cams 96 will engage the rollers on the bell crank 94 and again move the friction rollers 85 into contact with the finished vials. At about this time the rods 69 will be retracted to a predetermined point and the vials will be moved centrally on their supports by means of the friction rollers 85. Immediately after the vials have been moved to their central position on their supports, the friction rollers will be lifted from the finished vials and the rods will be retracted to their inactive positions. The endless carrier 7 is then moved another step to bring the next vial into bottoming position and to advance the finished vials toward the discharge chute.

In Figure 13 we have shown one form of feeding mechanism connecting the end of a necking machine 103 with the bottoming machine, and in which 104 designates the opening through which the necked blanks pass from the machine to a suitable incline from which they are picked up by means of clips 105 on an endless conveyor 106. This endless conveyor is moved step by step in timed relation to the carrier 7, and successively brings the blanks to station A from which they are transferred to the station B as fully described. The endless conveyor 106 passes over a driving sprocket wheel on a shaft 107, which is in turn driven by means of a sprocket chain 108 passing over a driving sprocket wheel 109 on a shaft 110 on the vial necking machine 103.

In Figure 14 we have shown somewhat diagrammatically the driving mechanism for the vial bottoming machine and the necking machine 103 at the other end thereof. In this mechanism 111 designates the driven shaft receiving power from a pulley 112, and having loosely mounted thereon a sprocket wheel 113, which is connected by means of a sprocket chain 114 with a sprocket wheel 115 on the driving shaft 116 of the vial necking machine. 117 is a similar sprocket wheel loosely mounted on the shaft 111 which is connected to a sprocket wheel 118 on the driving shaft 17 of the bottoming machine. When this combined form of drive is used the pulley 18 is eliminated.

Slidably mounted on the shaft 111 is a clutch member 119, which is arranged to connect the sprocket wheel 117 thereto and which is actuated by any suitable clutch actuating mechanism. 120 is a similar clutch

for connecting the sprocket wheel 113 to the shaft 111.

In the foregoing, we have described a bottoming machine in which the blanks are centered at the station C, are then successively moved to a plurality of heating stations, are separated and then bottomed at station E.

In our preferred form, however, the blanks are centered by means of adjustable guides, which guides extend from the station B to a point adjacent to the station corresponding to station D³. In this construction we may eliminate the plunger centering mechanism shown in the foregoing described drawings at the station C and also provide a supplemental preliminary separating device at the station d⁴ corresponding to station D⁴.

In our preferred form, as shown more particularly in Figures 18, 19 and 20, we have applied the same reference characters with the Figure 2 prefixed thereto, to designate the parts corresponding to the parts already described in detail in connection with the preceding figures. We have also described the various stations with small reference letters instead of capital letters, in order to avoid confusion.

In the preferred form of mechanism shown in these figures, there is provided means at one of the stations for preliminarily extending the vial blank. At the succeeding station there is provided mechanism for further extending the blank to such an extent that it will be separated into two vial-forming portions. At the third station these portions are forced inwardly into contact with a bottoming device such as already described. By providing for the separation of the vial blank in a series of stations, a much more uniform product is produced and the breaking of blanks which may occur where a single station operation is performed, is entirely eliminated.

Referring more particularly to these figures we have provided longitudinally extending guides 300 supported on brackets 301 which may be adjustably secured to the main frame of the bottoming machine by means of the slotted connections 302. These guides are provided in lieu of the centering rods 65 at station C in the construction described. It has been found that stationary guides extending approximately from station c to a point slightly beyond station d³ operate very successfully to maintain the blanks centrally on their supports. It is quite obvious that the guides 300 may be slightly flared outwardly at their receiving ends to insure the passage of the blanks therebetween.

In these figures we have also illustrated in detail the type of burners which we desire to use in connection with the various

forms of bottoming machines described herein. As illustrated, there is provided a main burner 303 having a single burner opening 304, and of such length that it extends approximately from station d' to a point slightly beyond d^4 . As the blanks are successively moved to the different stations they will be gradually heated to the proper temperature. Due to the provision of a single burner opening, the highly heated area of each of the blanks will be restricted to substantially the central portion, which insures separation at the proper point. At station d^4 there is provided the mechanism for preliminarily extending the blanks to form a central restricted portion 305. From this station the blank passes over a shorter burner 306 having a series of burner openings 307 formed therein, adapted to heat the entire restricted portion 305 of the blanks. At this station the separation of the blanks into two vial-forming portions is completed and these portions are then carried to the station e where they are brought into engagement with the bottoming device 298. The provision of the extended rollers 211' and 212', corresponding to the rollers 11' and 12' already described, insures the supporting of the separated portions of the blanks in proper position on their respective supports.

The operating mechanism for producing the separation in stages of the blanks, is illustrated in detail in Figure 20. This comprises a bearing 308 swingingly carried on the stub shaft 309 having a crank 310 formed thereon which is connected by means of an adjustable link 311 to the bell crank lever 312, one end of which co-operates with a cam 313, corresponding in construction and operation to the cams 96. It will be apparent that on opposite sides of the machines these cams 313 are carried by the shafts 225 and 225^a, respectively. Journaled in the bearing 308 on one end of the shaft 314, is an extending roller 315, positioned to operate on the blanks at the station d^4 to effect preliminary extension thereof as described. This roller 315 is continuously rotated by mechanism similar to that provided for rotating the rollers 85 at the bottoming station. On the opposite end of the shaft 314 is a second roller 316 positioned at the station d^5 , which operates in unison with the roller 315 and effects separation of the preliminarily extended blanks. An adjustable stop mechanism for the ends of the blanks is preferably provided at the stations d^4 and d^5 and comprises rods 317 and 318 having a connecting yoke 319. By properly timing the operation of the cam 313 the rollers 315 and 316 may be periodically rocked into engagement with the ends of the blank as they are brought there beneath to effect the operations described. It

will be understood that this mechanism is duplicated on opposite sides of the machine so that the ends of the blanks are subjected to exactly the same forces. In Figures 18 and 19 a large part of the mechanism described has been eliminated for sake of clearness.

Instead of feeding the blanks to the bottoming machine by a transfer mechanism such as illustrated in detail more particularly in Figures 10 and 11, we may feed the same either by hand or by a suitably constructed hopper. In Figures 21 to 24, both inclusive, we have illustrated such a hopper feed. In these Figures also we have indicated the previously described parts of the mechanism by the same reference characters having prefixed thereto the numeral 2. The hopper preferably comprises an inclined bottom 320, having one fixed side 321 and an adjustable side 322. Any desired means, such as brackets 323, having suitably slotted openings formed therein, may be provided for accomplishing this adjustment to accommodate the hopper to vials of different lengths. The hopper is preferably of such length that the receiving open end thereof may co-operate direct with the ejection opening 2104 of the necking machine 2103. The delivery end of the hopper extends over the receiving end of the bottoming machine and may be supported on any suitable bracket 324 carried by the frame 202 of this machine.

Below the bottom 320 of the hopper are a series of bars 325 and 326, which bars carry upwardly-projecting fingers 327 projecting through openings 328 in the bottom of the hopper. The bars 325 have a connection 329 with one end of each of the T or walking levers 330, while the bars 326 have a similar connection 331 with the opposite ends of the levers 330. Both of these levers have suitable pivotal supports 332 and are provided with downwardly-projecting portions 333 connected by a link 334 which causes the same to move in unison. For producing this movement, we may provide one of the pivots 332 with a crank arm 335 having a pivotal connection with the link 336, carried by the lever 337 pivotally supported at 338 on the bracket 339 secured to the main frame of the bottoming machine. The forward end of the lever 337 is provided with a roller 340 adapted to co-operate with a cam 341 on the end of the shaft 225^a provided at one side of the bottoming machine and already described in detail.

Extending laterally from the bracket 339 is a seat 342 having a projection 343 thereon, adapted to receive a compression spring 344, the opposite end of which surrounds a similar projection 345 on the lever 337. It will now be apparent that the cam 341

periodically operates the lever 337 through the mechanism described against the action of the compression spring 344 to lower the bars 326 and raise the bars 325. As soon as the high point on the cam 341 has passed from engagement with the roller 340, the compression spring will function to elevate the bars 326 and lower the bars 325 to their original positions. Each operation of this nature will release the vial blanks from engagement with the fingers 327 on one of the bars to permit the same to roll along the hopper bottom into engagement with the next series of fingers. By means of this mechanism a gradual feed of the blanks is insured and the rate of feed may be so controlled that it operates in timed relation both with the bottoming machine and the necking machine.

At its delivery end, the hopper is provided with a chute 346, adapted to deliver the blanks directly onto the supports 208 on the endless link belts 207 of the bottoming machine. Passage of the blanks to this chute may be controlled by means of a sliding gate 347 operated by a bar 348 suitably secured thereto and extending transversely of the hopper through slotted openings 349 in the opposite sides thereof. The opposite ends of the bars 348 are in turn suitably secured to levers 350 having a pivotal mounting 351 for their opposite ends. Intermediate their ends, the levers 350 are joined to pitman rods 352 secured to the transversely extending operating member 353. This operating member may in turn be connected to one of the T levers 330 so that the gate 337 is elevated and lowered in accordance with the movement of said lever. The chute 346 may also be provided with a stationary side 354 and an adjustable side 355, and preferably a guard 356 carried by the bracket 357, is provided for preventing the vial blanks from being delivered beyond the supports 208. Figures 25 and 26 illustrate clearly the types of blanks adapted to be operated upon by the present bottoming machine. The blanks shown in Figure 26, are adapted for the production of wide-mouthed vials.

It will be apparent that the provision of a hopper of this nature makes it possible to use the machine independently of the necking machine. When this is done, the vials, either necked or unnecked, may be manually placed in the hopper and the operation of the mechanism employed in connection therewith will insure an orderly delivery of the same.

From the foregoing it will be apparent that we have provided a machine which operates to bottom vials rapidly as the same are delivered thereto, irrespective of the manner in which this delivery is effected.

The advantages of our invention result

from the provision of a vial-bottoming machine having a plurality of heating stations, so that the blanks can be heated as rapidly as bottoms can be formed thereon, whereby the capacity of the machine is only limited by the time required for bottoming.

A further advantage results from the provision of means for connecting the bottoming machine to a necking machine, together with driving mechanism for both of said machines, which is so arranged that either of the machines can be connected or disconnected from the driving mechanism independent of the other machine.

We claim:

1. A vial bottoming machine having an endless carrier, a plurality of rotary vial blank supports thereon, a charging station, a finishing station, heating means between said stations, means for moving the carrier to bring the supports to such successive stations, means for rotating said supports to thereby rotate the ware thereon, means for placing blanks on the supports as they are brought to the charging station, and means for bottoming the blanks at the finishing station, substantially as described.

2. A vial bottoming machine comprising an endless carrier having a plurality of supports, means for rotating said supports to thereby rotate the ware thereon, a finishing station, means at the finishing station for manipulating successive blanks at the finishing station, means for moving the carrier to bring the supports to such successive stations, means for placing blanks on the supports as they are brought to the charging station, means for heating the blanks, and means for bottoming the blanks at the finishing station during their manipulation, substantially as described.

3. A vial bottoming machine having an endless carrier, a plurality of rotary vial blank supports to thereby rotate the ware thereon, worms for rotating the supports, a charging station, a finishing station, heating means between said stations, means for moving the carrier to bring the supports to the successive stations, means to place blanks on the supports as they are brought to the charging station, and means for bottoming the blanks at the finishing station, substantially as described.

4. A vial bottoming machine having a plurality of link belt carriers, a plurality of rotary vial blank supports on each of said carriers, means for rotating the supports to thereby rotate the ware thereon, the vial blank supports on one carrier being in alignment with the vial blank supports on the other carrier, a finishing station, means for moving the carrier to bring the supports to the successive stations, heating means in advance of the finishing station, means for successively placing blanks on the supports

in advance of the heating means, and blank manipulating means moved into and out of operative relation with the successive blanks for bottoming the blanks at the finishing station, substantially as described.

5 5. A vial bottoming machine having an endless carrier, a plurality of rotary vial blank supports thereon, means for placing blanks on the supports, means for centering 10 the blanks on the supports, a finishing station, means in advance of the finishing station for heating the blanks, means for moving said carrier to bring the blanks in a successive manner to the finishing station, 15 means for rotating the vial blank supports while at the finishing station to thereby rotate the ware thereon, and means at the finishing station for engaging and manipulating the successive blanks to finish the 20 bottoms, substantially as described.

6. A vial bottoming machine having an endless carrier, a plurality of rotary vial blank supports thereon, means for placing blanks on the supports, a bottoming station, 25 means for heating an intermediate portion of the blanks before reaching the bottoming station, means for moving the carrier to bring the supports to the successive stations, means for separating the blanks into two 30 parts before reaching the bottoming station, a bottom forming device arranged to be positioned between the separated portions of the blank, and manipulators at the bottoming station for moving the blanks towards each other on opposite sides of the bottoming device, substantially as described.

7. A vial bottoming machine having two endless carriers arranged side by side, means 40 for simultaneously moving said carriers intermittently step by step, spaced rotary blank supports on each of said carriers, the blank supports on one carrier being in alignment with the blank supports on the other 45 carrier, a track for each carrier, and means for continuously rotating the blank supports during a portion of their travel over said track and when at rest on said track, substantially as described.

50 8. A vial-bottoming machine having two endless carriers, sprocket wheels for each of said carriers, means for intermittently actuating one set of sprocket wheels for moving the carriers, a plurality of rotary supports on each carrier, the rotary supports on the one carrier being in alignment with the rotary supports on the other carrier, a track for each carrier, worm connections for rotating the supports, and driving connections for intermittently actuating the sprocket wheels and continuously rotating the worm connections, substantially as described.

65 9. A vial-bottoming machine having an endless carrier, means for feeding blanks to

said carrier, means for moving said carrier step by step, means for heating the blanks, a bottoming station, means for rotating the blanks at the bottoming station, means for separating the blanks into two parts at the 70 bottoming station, means for moving said separating means into contact with the vial blanks at a predetermined time to separate the blanks, a bottom forming device, means for moving said bottom forming device between the separated portions of the blank, means for moving said separated portions toward the bottoming device, said last mentioned means being arranged to be retracted after the bottoms have been formed, and means for again shifting the separating mechanism into contact with the vials to move them away from the bottoming device and to move them centrally on the carriers, substantially as described.

75 10. A vial machine comprising a flexible endless carrier, means for moving the carrier, a plurality of vial supports on said carrier, means for heating the blanks on said supports, and means for continuously rotating said blank supports independently of the travel of the carrier to rotate the blanks during the heating thereof, substantially as described.

80 11. A vial-bottoming machine, comprising an endless carrier, means for moving the carrier, vial blank supports thereon, means for positioning the blanks on said supports, means for heating the blanks, means for extending the blanks, means for separating the extended blanks and mechanism for forming a bottom on each portion of the separated blanks at such separated portions, substantially as described.

85 12. A vial-bottoming machine, comprising an endless carrier, means for moving the carrier, vial blank supports thereon, means for positioning the blanks on said supports and maintaining the blanks in position thereon, means for heating the blanks, means for extending the blanks, means for separating the extended blanks, and mechanism for forming a bottom on each portion of the separated blanks at such separated portions, substantially as described.

90 13. Means for separating vial-forming blanks in a bottoming machine, comprising a gripping and separating member for each end of the blanks, means for simultaneously moving said members into gripping engagement with the ends of the blanks, means for actuating said members to separate the blanks, a bottoming device, means for moving said device between the separated portions of the blank, and yielding means for moving the portions of the blanks into engagement with the bottoming device, substantially as described.

125 14. Means for separating vial-forming blanks in a bottoming machine, comprising 130

extending and separating members for each end of the blanks, means for moving certain of said members into gripping engagement with the ends of the blanks for extending 5 the same, means for actuating other of said members to separate the blanks, a bottoming device, means for moving said device between the separated portions of the blank, and means for moving the portions of the 10 blanks into engagement with the bottoming device, substantially as described.

15. Means for separating vial-forming blanks in a bottoming machine, comprising extending and separating members for each 15 end of the blanks, means for moving certain of said members into gripping engagement with the ends of the blanks for extending the same, means for actuating other of said members to separate the blanks, a bottoming device, means for moving said device between the separated portions of the blank, 20 means for moving the portions of the blanks into engagement with the bottoming device, and means for moving the finished vial away 25 from the bottoming device, substantially as described.

16. A vial bottoming machine having an endless carrier, a plurality of rotary vial blank supports thereon, driving means for 30 each support, means engaging said driving means to rotate the supports and thereby rotate the blanks, means for delivering blanks to said supports, and means for centering the blanks on said supports, substantially 35 as described.

17. A vial bottoming machine having an endless carrier, a plurality of vial blank supports thereon, a charging station, a finishing station, means for moving the carrier 40 step by step to bring the supports to the successive stations, means for placing blanks on the supports as they are brought to the charging station, means for centering the blanks on the supports, means for heating 45 the blanks as they are moved towards the finishing station, and blank manipulators and a bottom former for bottoming the successive blanks on the supports at the finishing station, substantially as described.

50 18. A vial bottoming machine, comprising an endless carrier, means for intermittently moving the carrier, a plurality of rotary vial blank supports thereon, driving means for rotating the supports while the carrier 55 is stationary, means for delivering blanks to the supports, and means for centering the blanks on said supports, substantially as described.

60 19. A vial-bottoming machine, comprising an endless carrier, means for moving the carrier, a plurality of positively rotated vial blank supports thereon, means for delivering blanks to said supports, means for centering the blanks thereon, means for gradually 65 heating the blanks during the movement of

the carrier, and means for continuously rotating said blanks during the heating thereof.

20. A vial bottoming machine, comprising an endless carrier having a series of rotating 70 blank supports, means for moving the carrier step by step and permitting the carrier to dwell between shifts, and means for rotating the supports during the movement of the carrier as well as during dwells between 75 movements, substantially as described.

21. A vial bottoming machine, comprising an endless carrier having a plurality of rotating vial blank supports thereon, means for delivering blanks to said supports, means 80 for centering the blanks on said supports, a plurality of operating stations beyond the centering means, means for moving the carrier in a step by step manner and permitting dwells between said movements, and means 85 for rotating the supports during their movement and during the dwells between movements, substantially as described.

22. A vial bottoming machine, comprising a plurality of endless carriers, spaced rotary 90 blank supports on each of said carriers, the supports on one of said carriers being in alinement with the supports on the other of said carriers, means for delivering blanks to said supports, a plurality of operating stations, means for simultaneously moving the carriers step by step and to permit the carriers to dwell at the operating stations, and means for rotating the blank supports during the movement of the carrier and also 95 when at the operating stations, substantially as described.

23. A vial bottoming machine, comprising a plurality of endless carriers, a plurality of rotary blank supports on each carrier, the supports on one of said carriers being in alinement with the supports on the other of said carriers, means for delivering blanks to said supports, a plurality of operating stations beyond the blank delivering means, 110 means for heating the blanks at and between some of the operating stations, means for moving the carriers step by step and for permitting the blank supports to dwell in a successive manner at each of the operating stations, means for rotating the blank supports during their shifting and when at rest at the operating stations, and means at the last station for forming bottoms on the blanks, substantially as described. 115

24. A vial bottoming machine having two endless carriers arranged in parallel relation to each other, a plurality of rotary blank supports thereon, means for delivering blanks to said supports, a plurality of operating stations beyond the blank delivering means, means for heating the intermediate portions of the blanks, means for simultaneously shifting the carriers step by step and to permit the supports to dwell at the oper- 125 130

ating stations, means at one of said stations for separating the blanks intermediate their ends at the heated portions, and means at the last station for forming a bottom on each of the separated portions, substantially as described.

25. A vial bottoming machine, comprising two carriers arranged parallel to each other, a plurality of rotary blank supports on each 10 of said carriers, the vial blank supports on the respective carriers being in alinement, means for delivering blanks to said supports, a plurality of operating stations beyond the blank delivering means, means for heating 15 the blanks at some of said stations and intermediate of some of said stations, means for moving the carriers step by step in timed relation to each other and to permit the supports to dwell at the successive stations in a 20 successive manner, means for rotating said blank supports during such dwells, and blank manipulating devices at some of the stations, the last of said stations having means for bottoming two vials, substantially as de- 25 scribed.

26. A vial bottoming machine having a series of blank manipulating stations, means for successively bringing blanks to said stations, the next to the last of the manipulating 30 stations being a separating station at which the blank is separated into two vial forming portions, a burner extending across a plurality of stations preceding the separating station and having a single longitudinal 35 opening extending across a plurality of said stations, a burner at the separating station having a plurality of openings, and vial bottoming means at the last station, substantially as described.

40. 27. Heating means for vial-bottoming machines, comprising a longitudinally extending burner having a single opening therein, and a supplemental burner having a plurality of openings therein, substantially as de- 45 scribed.

28. In a vial bottoming machine, means for heating the intermediate portions of long blanks for forming two vials from each blank, rollers for partially extending said 50 blanks, a second set of rollers for successively separating the extended blanks into two vial forming portions, and means for bottoming the separated portions of said blanks, substantially as described.

55. 29. A vial bottoming machine, comprising a plurality of operating stations for operating on vial forming blanks, means for heating the intermediate portions of the blanks at some of the stations and intermediate said 60 stations, rollers at one of the stations for partially extending the vial blanks, another set of rollers for separating the blanks into two vial forming portions at the next station, and bottom forming devices at the sta-

tion beyond the separating station, substantially as described. 65

30. A vial-bottoming machine, comprising traveling carriers for the vial blanks, means for delivering the blanks thereto, a heating station, a plurality of operating stations, rotating means at one of said operating stations for partially extending the vial blanks, 70 rotating means at another of said stations for separating the vial blanks, and means for moving said rotating members into engagement with said blanks, substantially as described. 75

31. In a vial-bottoming machine, a heating station, a plurality of operating stations, means for successively delivering blanks to 80 said stations, rotating means at one of said operating stations for producing an extension of the vial blanks, rotating means at another of said operating stations for separating said extended blanks, and means for 85 bottoming the separated portions of said blanks, substantially as described.

32. An extending mechanism for vial blanks, comprising a roller, means for rotating said roller about an axis at substantially 90 right angles to the length of the blanks, and means for moving said roller into and out of contact with the vial blank to be extended, substantially as described.

33. A vial bottoming machine, comprising 95 an endless carrier having rotary vial blank supports thereon, a hopper adapted to contain a series of vial blanks, and blank manipulators for delivering the blanks from the hopper to the supports in a successive manner, said manipulators being arranged to maintain a plurality of blanks separated from each other within the hopper, substantially as described. 100

34. A vial bottoming machine, comprising 105 an endless carrier, vial blank supports thereon, means for positioning the blanks on said supports, means for moving the carrier successively to a plurality of heating stations, and then to an extending station and to a separating station, means for heating the blanks at each of the heating stations, laterally movable manipulators for successively extending the blanks at the extending station, other laterally movable manipulators for successively separating the extended blanks at the separating station, and means for forming a bottom on each portion of the separated blanks at the separated portions, 110 substantially as described. 115

35. A vial bottoming machine, comprising 120 a traveling carrier for the vial blanks, means for delivering the blanks thereto, a heating station, a plurality of operating stations, means at one of said operating stations rotatable at substantially right angles to the axis of the blanks for partially extending the blanks, similar rotatable means at an- 125

- other of said stations for separating the blanks, and means for moving said rotating means into engagement with the blanks, substantially as described.
- 5 36. In a vial bottoming machine, means for heating the vial blanks, means for partially extending said blanks, means for separating the extended blanks, means for moving the extending and separating means into 10 and out of engagement with the blanks, and means for bottoming the separated portions of said blanks, substantially as described.
- 15 37. A vial bottoming machine, comprising a plurality of heating stations and a plurality of operating stations, means for partially extending the vial blanks at one of said operating stations, means for separating the blanks at another of said operating stations, and means for moving said extending and 20 separating means into and out of engagement with the blanks.
- 25 38. In a vial bottoming machine, a plurality of worms, carriers adjacent said worms, blank supports on said carriers, means carried by said blank supports for engagement with said worms and means for rotating said worms, substantially as described.
- 30 39. In a vial bottoming machine a plurality of worms, carriers adjacent said worms, means for imparting a step by step movement to said carriers, blank supports on said carriers, means on said blank supports for engagement with said worms, and means for 35 rotating said worms, substantially as described.
- 35 40. In a vial bottoming machine, a plurality of worms, means for rotating said worms,
- carriers adjacent said worms, means for moving said carriers independently of said worms, blank supports on said carriers, and 40 means on said blank supports for engagement with said worms, substantially as described.
- 45 41. In a vial bottoming machine, a blank carrier, rotary blank supports on said carrier, means for moving said carrier intermittently, and gearing for simultaneously rotating a plurality of said supports to rotate the blanks carried thereby during the movement of the carrier and when said carrier is at rest, substantially as described.
- 50 42. In a vial bottoming machine, a blank carrier, means for imparting a step by step movement to said carrier to bring the same successively to a plurality of different stations, blank supports on said carrier, and means for simultaneously rotating a plurality of said supports while the carrier is at rest, substantially as described.
- 55 43. In a vial bottoming machine, a blank carrier, a plurality of heating stations, means for simultaneously moving the carrier to successively bring different portions thereof to the different stations, blank supports on said carrier, and means for rotating the blank supports while the carrier is at rest, whereby the blanks at the different stations are rotated, substantially as described.

In testimony whereof, we have hereunto set our hands.

BENJAMIN T. HEADLEY.
PARKE H. THOMPSON.
DAVID IRVIN DU BOIS.
